UNITED STATES PATENT OFFICE.

JOHN BIRNEY, OF PHILADELPHIA, PENNSYLVANIA.

CARPET.

SPECIFICATION forming part of Letters Patent No. 634,797, dated October 10, 1899.

Application filed March 22, 1893. Renewed August 25, 1899. Serial No. 728,511. (Specimens.)

To all whom it may concern:

Be it known that I, JOHN BIRNEY, a citizen of the United States, residing at Philadelphia, in the county of Philadelphia and State of Pennsylvania, have invented certain new and useful Improvements in Carpets, of which the following is a specification, reference being had therein to the accompanying drawings.

My invention relates to certain improvements in carpets, and has for its object to provide a durable carpet which may be manufactured at small cost.

The invention consists in the novel construction of carpet hereinafter described and claimed.

In the accompanying drawings, Figure 1 is a diagrammatic plan view of a piece of carpet woven in accordance with my invention, and Fig. 2 is a sectional view of the same on the line 2 2, Fig. 1.

In weaving a carpet in accordance with my invention I employ two sets of warp-threads A and B, one of which is of the color of the figure to be woven in the carpet and the other being the complementary or ground color. I also employ a heavy filling-weft C and a very thin binding-weft D. The filling-weft causes the carpet to present a ribbed appearance, and the binding-weft not only serves to maintain the same colored warp uppermost throughout the carpet, but also causes the warp-threads to bind tightly around the filling-weft. The filling-weft is formed of a cord of jute or other suitable material, while the binding-weft may be of cotton. The filling-wefts are arranged together as closely as possible, so that there will be no break in the color of the surface and the presence of the minute binding-weft will not be noticed in the finished carpet.

In the weaving of a figured fabric the colors and relative positions of the upper and lower

warp-threads must be changed, and this is accomplished by weaving in the manner shown at α in the drawings, the positions of the heddles carrying the varicolored warp-threads being so changed as to bring the then lower warp to the upper shed, and vice versa, immediately after the filling-weft pick and before the binding-weft pick. The binding-weft is then thrown across the shed and such portion only of the shed changed as may be required to produce the pattern, the binding-weft and filling-weft being at intervals required by the pattern in the same shed, so that the color is changed without losing the rib effect produced by the binding-weft, excepting at small intervals throughout the width of the fabric.

I am aware that it has heretofore been proposed to manufacture plain or striped or checked fabrics with alternate filling-weft and binding-weft threads to produce a rib effect; but in such cases where the change of color takes place the binding-weft must be altogether omitted and only plain square checks can be produced, while the rib effect is entirely lost.

Having thus described my invention, what I claim, and desire to secure by Letters Patent, is—

A figured carpet fabric comprising varicolored warps, and alternate filling and binding weft threads, said filling and binding wefts being bound together in a single shed at each change of color to produce the necessary pattern, substantially as described.

In testimony whereof I affix my signature in the presence of two witnesses.

JOHN BIRNEY.
